ESCAPEMENT TYPE SWITCH

Gerald Deakin, New York, N. Y., assignor to International Standard Electric Corporation, New York, N. Y., a corporation of Delaware

Application February 5, 1942, Serial No. 429,655

15 Claims. (Cl. 179—27.51)

This invention relates to new and useful improvements in electrical switching devices and more particularly to switching devices of the escapement type.

The main feature of the present invention has to do with the mounting of contact wipers on the ratchet wheel of the escapement switch. The ratchet teeth being in a relatively large wheel, accurate positioning is possible in spite of the simplicity and inexpensiveness of the structure. The ratchet wheel is made of thin stock but so mounted and guided as to insure proper contact between terminals and the wipers, even where the latter are mounted on both faces of the ratchet wheel.

In accordance with the present invention, the escapement switch is or preferably a plurality of escapement switches are, coupled to a driving shaft by means of a clutch which permits the continued rotation of the shaft while the escapement mechanism holds the switch against movement.

A feature of the invention has to do with the construction of the clutch.

Another feature of the invention is concerned with the stopping and the restoration to normal of the escapement switch. The escapement wheel which carries the switching wipers is provided with a lug into the path of which a stop may be moved. The stop and the electro-magnetic operating means therefor are in accordance with a further feature of the present invention common to a plurality of escapement switches.

The escapement magnet and pawl are provided on a movable mounting so that they may be bodily displaced with respect to the escapement wheel with which they normally cooperate, thus freeing the wheel for a return to normal in one continuous movement as distinguished from the step-by-step movement performed while the escapement wheel and pawl are cooperating.

In accordance with a feature of the present invention, the escapement magnets and pawls of a plurality of switches are provided with a common mounting so that they can all be moved in unison and the movement of the mounting structure is controlled by the electromagnetic means which controls the moveable stop.

These and other features of the invention will be explained in greater detail in the following description of a preferred embodiment as applied to the drawings, in which:

Fig. 1 is a vertical cross-section, partly in end elevation, of an escapement switch;

Fig. 2 is a side elevation of an escapement wheel;

Fig. 3 is a side elevation of an escapement switch unit mounted in the frame;

5 Fig. 3a is a side elevation of an escapement switch unit with the escapement magnet energized;

Fig. 4 is a rear view of the terminal bank of an escapement switch;

10 Fig. 5 is a side elevation of a mounting structure including 10 escapement switch units;

Fig. 6 is a top plan view of said mounting structure; and

Fig. 7 is a sectional view along line 7—7 of Fig. 15 5, showing the switch in the stopping position.

Each escapement unit comprises a hardened steel ratchet wheel 1. One set of bridging brushes 2 is mounted on one side of the ratchet wheel by means of a rivet 3 or the like, but insulated from the wheel 1 by the insulation 4. The brush has two relatively long wipers 5 and two relatively short wipers 6. A similar bridging brush 7 is mounted in alignment with brush 2 on the other side of the wheel 1 and a corresponding pair of bridging brushes 8 and 9 are mounted on the wheel 1, 180° displaced with respect to brushes 2 and 7. As best shown in Fig. 2, the brushes 8 and 9 are reversed with respect to the brushes 2 and 7 so that the wipers of the 25 two sets of brushes are mirror images of one another.

In the normal position, the long wipers, such as 5 of the two pairs of brushes 2, 7 and 8, 9 contact with relatively long terminals 12, 13 molded 35 in a contact bank 14 of insulating material, and the short wipers, such as 6, of the brushes contact with short terminals such as 17, 18 molded into the contact bank 14. The contact bank has a semi-circular cut-out portion 19 within which 40 the ends of the terminals project into the path of the ends of the brushes.

The molding 14 has within its semi-circular cut-out portion a central groove 20 within which the ratchet teeth project, the wheel being held in 45 position by ridges such as 21 forming a neck in the groove 20.

The disc 1 is driven by means of a shaft 22 through the agency of a friction clutch mounted on the shaft and longitudinally slidably thereon. 50 Thus the neck 21 will guide the rotation of the ratchet wheel without danger of binding.

The clutch is composed of an element 24 which is keyed in a slot 25 of the driving shaft 22 and is thus forced to rotate with the shaft although 55 it is free to slide along the shaft. The clutch

element 24 has a hub 25a carrying a hard metal washer 26. On the washer 26 is seated the ratchet wheel 1 between two felt washers 27. One of the felt washers bears against the face of clutch element 24 and the other felt washer against the face of a second clutch element 28. The clutch element 28 is keyed into slot 29 of hub 25 and is forced against the felt washer 27 by means of a spring spider 30 held in position by a ring 31 on the hub 25. The felt washers 27 are saturated in oil and the clutch assembly is free to rotate with the shaft 22 while the ratchet wheel is held against displacement.

In the embodiment here disclosed, 13 terminals project from the molding 14 within the path of the contact brushes on the ratchet wheel. Some rows may consist of four terminals like 12, 13, 17 and 18, and others of only two long terminals. Some of these terminals may be in the form of common feeder strips extending parallel to an adjacent row of terminals. Diametrically opposite contact brushes engage the terminals projecting from the bank 14 only when one engages the first set of terminals and the other the thirteenth set of terminals. In all other positions of the ratchet 1, only one set of brushes makes contact at a time.

In Fig. 4, which is a rear view of the terminal bank 14, a contact bank is illustrated with two rows of thirteen long terminals, like 10, 11 and 12, 13, two feeder strips and two sets of short terminals like 17, 18, which may serve as home terminals of a selector switch. Obviously, many other types of contact bank arrangements are possible.

The framework for supporting an assembly for 10 units consists of one right end support 52, a middle support 53 and a left end support 54. The end supports are provided with mounting lugs 55. The three supports are held together by an upper bar 56 and a lower bar 57 secured thereto by means of screws 58 which not only engage the supports but also screw-threaded inserts in the molded banks 14 of the escapement units. The shaft 22 is journaled in the three supports 52, 53, 54 by means of ball-shaped bearings 59, held in position by plates 60.

The drawings illustrate an assembly consisting of ten units which are driven from a continuously rotating driving shaft 33 provided with a bevelled driving gear 34, with which a driven gear 35 is normally caused to mesh by means of a spring (not shown). The gears may be moved apart under the control of a forked armature 36 pivoted at 37 and operable by means of a clutch magnet 38 mounted on one of the lugs 55. A spring 39 normally urges the armature 36 away from collar 40 on hub 41 of the bevelled gear 35 and against a collar 42 thereon. The bevelled gear 35 with its collar is mounted on the end of shaft 22 and thus when gears 35 and 34 are permitted to mesh, then all the clutches mounted on shaft 22 will be rotated. None of the escapements will be moved, however, because normally the upper end of a pawl 43 engages a ratchet tooth of the associated ratchet wheel 1 and holds the wheel against displacement.

The pawl 43 is fastened to armature 44 of escapement magnet 45 pivotally mounted at 46 on an extension of a return pole-piece 47 of magnet 45. This magnet assembly is mounted by means of screws 48 on a rocker frame 49. A coiled spring 50 fastened to the lower end of the pawl 43 and to the rocker frame 49 normally holds the pawl in the locking position against a back-

stop formed by an extension 51 of the return pole-piece 47.

When the magnet 45 is energized, it will attract its armature 44 against the tension of spring 50 and move the upper end of pawl 43 out of the path of the ratchet tooth with which it is in engagement, thus allowing the wheel 1 to be rotated by shaft 22 through the agency of clutch 24, 28 until it is stopped by the lower end of the pawl 43 engaging another ratchet tooth (Fig. 3a). The spacing of the upper and lower ends of the pawl 43 is such that the wheel 1 is permitted to advance a sufficient distance for the brushes thereon to break contact with the terminals on which they are resting and make contact with the next set of terminals.

When the magnet 45 becomes deenergized, the pawl 43 will be moved by the spring 50 back into the position shown in Fig. 3. The wheel 1 is permitted to move until stopped by the upper end of the pawl 43, but this distance is less than one-half a tooth and not sufficient for the brushes to break contact with the terminals on which they are resting.

25 The rocker arm 49 is rotatably mounted on a shaft 61 which is secured to the three supports 52, 53, 54 by brackets 62. The rocker arm 49 is held in this normal position under the tension of a spiral spring 63 (Fig. 7) which is attached at one 30 end to a projection 64 of the rocker arm and at the other end to the center support 53.

Means are provided for simultaneously returning all the escapement units to their normal position no matter in what off-normal position they 35 may be. This means consists of two release magnets 65, one at each end of the assembly (see Fig. 3) and a stop-plate 66 which extends across the assembly and rests in grooves 67 in the bases 52a, 54a of end supports 52 and 54. The plate 40 66 has ten slots 66a straddling the ten ratchet wheels.

When the release magnets 65 are energized, they attract their armatures 68 normally resting against projections 69 on the bases of the end 45 supports and into engagement with a nose 70 on the rocker arm 49. This will force the rocker arm with its attached pawl magnets away from the ratchet wheels into the position shown in Fig. 7. An arm 71 of the rocker arm 49 engages 50 now a bell-crank 72 and causes its rotation around a pivot point 73 against the tension of a spring 75. The upper end of the bell-crank 72 is hinged at 73a to the plate 66 and swings it from the position shown in Fig. 3 into the position shown in Fig. 7. In this position, the stop-plate 55 66 engages one of two lugs 74 provided on each wheel 1, the lugs 74 and stop-plate 66 being at other times in the relative positions illustrated in Figs. 3 and 3a. When the plate 66 engages a lug 74, then the rotation of the ratchet wheel 60 stops. There is sufficient play in the mechanism to insure that first the rocker arm is operated to disengage the ratchet wheel, and then the stop-plate 65 is moved into position, although the pawl should engage wheel 1 before the stop-plate releases it when magnets 65 are deenergized.

After sufficient time has elapsed to allow all 70 of the ratchets to reach the locking position, the magnet 65 is deenergized and allows rocker arm 49 and the associated magnets 45 and pawls 43 to return into the position shown in Fig. 4. The stop-plate 66 will now be moved by spring 75 to free the lugs 74, whereupon the ratchets will rotate a short distance until they are stopped by 75 the upper ends of the cooperating pawls 43.

The entire assembly is covered by a dust-tight cover 75, which is sealed in position as indicated at 76.

All the space at the rear of the assembly is filled in, terminal blocks 17 (Fig. 6) being fitted into the space at the ends and at the counter between the escapement units.

It will be noted that the toothed escapement disc of each escapement unit is many times larger than the usual ratchet-wheel of conventional switches. It is desirable that this disc shall at least be greater than half the inner diameter of the cooperating contact arc, and in fact it is preferable to make this disc even larger than the "wiping circle," i. e. the circle along which the wipers make contact with the bank terminals. By using such an extraordinarily large disc the accuracy of positioning of the contacts is enhanced, and the escapement teeth, which must withstand repeated impact against the escapement pawls are made large and sturdy. Furthermore for a given angular velocity of the rotary assembly (i. e. brush-and-ratchet-wheel assembly) and a given moment of inertia thereof, the impact force is less with a large disc than a small one, if the springiness of the pawls is such as to bring the assembly to rest within the same angle in both cases.

Unfortunately, however, increasing the size of the ratchet-wheel increases the moment of inertia of the rotary assembly. According to my invention this moment of inertia is made small even with a large disc by making the disc so thin that it is not even self-supporting, i. e. so thin that it would be subject to warping or distortion under the reaction of the brushes, etc. or under other forces to which it is subjected. Then the arcuate guiding ridges 21 are provided to support the disc against such distortion. Still further reduction of the moment of inertia is attained by mounting the four brushes with their sixteen wipers directly on the ratchet disc, and by arranging that the "wiping circles" shall be closely adjacent the faces of this disc, so that the brushes need not have great length. By all these measures a very high speed switch capable of operating at the rate of 60 steps a second or more with long life and accurate registry of the wipers against the contacts is made possible.

What is claimed is:

1. In an escapement switch, a ratchet wheel, wipers projecting at least from one face of said wheel, a bank of contacts cooperating with said wipers, and a guide engaging the ratchet wheel near the periphery thereof.

2. In an escapement switch, a ratchet wheel, a shaft on which said wheel is centrally mounted, wipers projecting at least from one face of said wheel, a bank of contacts cooperating with said wipers, and a guide formed in said bank engaging the faces of the wheel near the periphery thereof.

3. In an escapement switch, a ratchet wheel, wipers projecting from both faces of the wheel, a contact bank having a groove within which the wheel is guided near its periphery, and contact springs projecting from the bank on the two sides of the groove into engagement with the wipers.

4. In a switch, a disc, wipers mounted on said disc, a terminal bank with which the wipers cooperate, a driving shaft for the disc, a spring-pressed friction clutch for coupling said disc to said shaft, comprising a first element having a hub keyed to said shaft and longitudinally mov-

able thereon, a second clutch element keyed to said hub and longitudinally movable thereon, a spring pressing the second towards the first element, a washer loosely mounted on said hub between the two elements and on which said disc is seated, and felt washers between said elements and the disc.

5. In an escapement switch, a plurality of ratchet wheels, wipers mounted on each ratchet-wheel, a terminal bank with which the wipers cooperate, a driving shaft for the ratchet-wheels, a spring-pressed friction clutch for each ratchet-wheel to couple it to said shaft, each clutch comprising a first element having a hub keyed to said shaft and longitudinally movable thereon, a second clutch element keyed to said hub and longitudinally movable thereon, a spring pressing the second towards the first element, a washer loosely mounted on the hub between the two elements and on which the ratchet wheel is seated, and felt washers between said elements and the ratchet wheel.

6. In an escapement assembly, a plurality of escapement units, each comprising a ratchet wheel, wipers mounted thereon, a terminal bank of insulating material having a groove, terminals projecting from said bank, a framework on which the banks for a plurality of units are mounted side by side with the ratchet-wheel of each unit in alignment with the groove in a bank and projecting therein and the wipers in the path of the ends of said terminals, a common driving shaft for all the ratchet-wheels, a clutch for each ratchet-wheel to couple it to said shaft, an escapement pawl for each escapement wheel, and a movement mounting for the escapement pawl bodily to move it towards and away from the escapement wheels.

7. In an escapement assembly, a plurality of escapement units, each comprising a ratchet wheel, wipers mounted thereon, a terminal bank of insulating material having a groove, terminals projecting from said bank, a framework on which the banks for a plurality of units are mounted side by side with the ratchet-wheel of each unit in alignment with the groove in a bank and projecting therein and the wipers in the path of the ends of said terminals, a common driving shaft for all the ratchet-wheels, a clutch for each ratchet-wheel to couple it to said shaft, an escapement magnet and pawl operated thereby for each escapement wheel, a movable mounting for the escapement magnet and pawl assemblies bodily to move them towards and away from the escapement wheels, a movable stopping means for all the escapement wheels, and common means for moving said mounting and stopping means.

8. In an escapement switch, a ratchet wheel, two sets of wipers mounted on the two sides of the ratchet-wheel 180° displaced with respect to one another, a terminal bank of insulating material having a semi-circular cut-out portion with a groove in said cut-out portion having a neck, terminals projecting from said bank to form arcs within said cut-out portion on the two sides of said groove, means for mounting said ratchet-wheel in alignment with the groove and projecting therein beyond the neck and the wipers in the path of the ends of said terminals, a driving shaft for the ratchet-wheel, a friction clutch for coupling said ratchet-wheel to said shaft, an escapement magnet and pawl for said escapement wheel, and a shaft on which the escapement magnet and pawl are mounted for bodily move-

ment towards and away from the escapement wheel.

9. In an escapement switch, a ratchet wheel, two sets of wipers mounted on the two sides of the ratchet-wheel 180° displaced with respect to one another, a terminal bank of insulating material having a semi-circular cut-out portion with a groove in said cut-out portion having a neck, terminals projecting from said bank to form arcs within said cut-out portion on the two sides of said groove, means for mounting said ratchet-wheel in alignment with the groove and projecting therein beyond the neck and the wipers in the path of the ends of said terminals, a driving shaft for the ratchet-wheel, a spring pressed friction clutch for coupling said ratchet-wheel to said shaft, and escapement magnet and pawl for said escapement wheel, a pivoted mounting for the escapement magnet and pawl assembly, and a magnet for rocking said pivoted mounting to move said assembly towards and away from said ratchet wheel.

10. In an escapement assembly, a plurality of escapement units, each comprising a ratchet wheel, two sets of wipers mounted on the two sides of the ratchet-wheel, a terminal bank of insulating material having a semi-circular cut-out portion with a groove in said cut-out portion having a neck, terminals projecting through said bank to form arcs within said cut-out portion on the two sides of said groove, a framework on which the banks for a plurality of units are mounted side by side with the ratchet-wheel of each unit in alignment with the groove in a bank and projecting therein beyond the neck and the wipers in the path of the ends of said terminals, a common shaft for all the ratchet-wheels and projecting therethrough, a spring-pressed friction clutch for each ratchet-wheel to couple it to said shaft, a mounting for said clutch on said shaft for insuring its rotation therewith and permitting its displacement longitudinally along the shaft, electromechanically controlled driving means for said shaft, an escapement magnet and a double-ended escapement pawl for each escapement wheel, a common shaft on which all the escapement magnet and pawl assemblies are pivotally mounted for bodily movement towards and away from the associated escapement wheels, a movable common stop-plate for all the escapement wheels, stop-lugs projecting from the escapement wheels, and means for moving said stop-plate into and out of the path of said stop-lugs.

11. In an escapement assembly, a plurality of escapement units, each comprising a ratchet wheel, two sets of wipers mounted on the two sides of the ratchet-wheel 180° displaced with respect to one another, a terminal bank of insulating material having a semi-circular cut-out portion with a groove in said cut-out portion

having a neck, terminals projecting through said bank to form arcs within said cut-out portion on the two sides of said groove, a framework on which the banks for a plurality of units are mounted side by side with the ratchet-wheel of each unit in alignment with the groove in a bank and projecting therein beyond the neck and the wipers in the path of the ends of said terminals, a common shaft for all the ratchet-wheels and projecting therethrough, a spring-pressed friction clutch for each ratchet-wheel to couple it to said shaft, a mounting for said clutch on said shaft for insuring its rotation therewith and permitting its displacement longitudinally along the shaft, electromechanically controlled driving means for said shaft, an escapement magnet and a double-ended escapement pawl for each escapement wheel, a common shaft on which all the escapement magnet and pawl assemblies are pivotally mounted for bodily movement towards and away from the associated escapement wheels, a movable common stop-plate for all the escapement wheels, stop-lugs projecting from the escapement wheels, and an electromagnet for moving said stop-plate into and out of the path of said stop-lugs and for rocking the pivotal mounting of said assemblies.

12. An escapement switch comprising an arcuate bank of contacts, wipers for wiping over said contacts with a substantial pressure, a rotatable toothed disc upon which said wipers are mounted, said disc having a diameter at least substantially half as great as the internal diameter of said arcuate bank and being so thin as to be subject to distortion by the reaction of said pressure, means for urging said disc to rotate, escapement means cooperating with the teeth of said disc for controlling the rotation of said disc, and stationary support means bearing against said disc near the periphery thereof to resist such distortion.

13. An escapement switch according to claim 12 wherein said contacts are symmetrically disposed on both sides of said disc and wherein said wipers are mounted symmetrically on both faces of said disc whereby the forces tending to distort said disc are minimized.

14. An escapement switch according to claim 12 wherein said means for urging said disc to rotate include a power driven constantly rotating shaft and means for transmitting a rotational couple from said shaft to said disc while permitting free movement of said disc longitudinally of said shaft.

15. An escapement switch according to claim 12 wherein said means for urging said disc to rotate include a rotatable shaft and means for transmitting a rotational couple from said shaft to said disc while permitting free movement of said disc longitudinally of said shaft.

GERALD DEAKIN.
